UNITED STATES PATENT OFFICE.

WALTER A. FOURNESS, OF NEW YORK, N. Y.

APPARATUS FOR PRODUCING GAS.

No. 829,518.

Specification of Letters Patent.

Patented Aug. 28, 1906.

Application filed September 27, 1905. Serial No. 280,286.

To all whom it may concern:

Be it known that I, WALTER A. FOURNESS, of the city, county, and State of New York, have invented a new and useful Improvement 5 in Apparatus for Producing Gas, of which the following is a specification.

The invention relates to the manufacture of water-gas or carbureted water-gas; and it consists in certain novel improvements embodied in an apparatus hereinafter described.

These improvements include—

First. In combination with a gas-generator or a retort and a casing having a chamber inclosing said retort, a single device whereby 15 the water-gas from said generator may be diverted into the retort and the producer-gas diverted into the casing-chamber. The said device is also preferably constructed so that on opening the passage leading from generator to retort it closes simultaneously the passage leading from generator to retort-casing and vice versa.

Second. The specific construction of said diverting device is in the form of a movable 25 valve which normally closes the passage leading to the casing-chamber by its own gravity which may be retained in position to close either passage and which is so arranged as not to be liable to stick or become clogged.

Third. The expelling of nitrogen and other impure gas from the top of the generator or from a collecting-chamber there located by means of a steam-jet, while at the same time the escape of water-gas from the generator at 35 the outlet provided for said water-gas is prevented. In this way the nitrogen is kept from mixing with and adulterating the water-gas.

Fourth. The admission of oil-jets into the 40 generator and to the first retort of a series of said retorts, thereby dividing the carbureting material between them and in this way preventing the carbonization of an excess of oil in the generator and the carrying over of 45 oil from the retort into the condenser, scrubber, or hydraulic main and also insuring the complete decomposition of the oil in the retorts by reason of its passage through them successively.

Fifth. The various combinations and instrumentalities more particularly set forth in the claims.

In the accompanying drawings, Figure 1 is a plan view of my apparatus, showing in section the walls of the casing-chamber inclosing the retorts. Fig. 2 is a vertical longitudi-

nal section showing the generator 1 in elevation. Fig. 3 is a vertical transverse section on the line x x of Fig. 1. Fig. 4 is a vertical section of valve-chamber 4 with its valve and adjacent parts. Figs. 5 and 6 are sections showing in detail the device for raising a controlling-valve and for holding the valve in adjusted position.

Similar numbers of reference indicate like 65 parts.

For convenience the gas which results from the blowing of air through the fuel in the generator is hereinafter termed "producer-gas" and the gas which results from the blowing of 70 steam through said fuel is hereinafter termed "water-gas."

Water-gas in my present apparatus is converted into carbureted water-gas or, as it is sometimes termed, "oil and water gas" by introducing oil into both generator and retort, as explained farther on. As my apparatus is here illustrated there are two generators, one of which makes water-gas, while the other makes producer-gas, the water-gas going to 75 retorts and the producer-gas going to a casing-chamber containing said retorts; but either generator may be used independently of the other, and this because there is provided at the gas-outlet of each generator the aforesaid 80 single device, whereby during the making of producer-gas by that generator said producer-gas may be diverted into the casing-chamber to heat the retort and whereby during the subsequent production of water-gas 85 said water-gas may be diverted into the retort for fixing or carbureting.

The generators which are shown at 1 and 2 are of the usual construction, lined with fire-brick, and provided with grates and ash-pits. The gas-conveying pipe 3 of generator 1 communicates with a valve-chamber 4 in the vertical pipe 5, and the gas-conveying pipe 6 of generator 2 communicates with a valve-chamber 7 in the vertical pipe 8. 90 Above the valve-chambers 4 and 7 the pipes 5 and 8 are connected by a horizontal pipe 9. The vertical pipe 5 extends above the valve-chamber 4 and is closed on top. It communicates by pipe 10 with a vertical pipe 11, 95 closed above and connected at its lower end to one extremity of the uppermost member of a bank of three parallel retorts 12 13 14. The other end of the highest retort 12 is connected to the corresponding end of the next 100 retort 13, and the farther extremity of retort 13 is connected to the corresponding ex-

tremity of retort 14. Retort 14 is connected by pipe 15 (dotted lines, Figs. 1 and 2) with the lowermost of another and similar bank of three retorts 16 17 18, which communicate 5 with one another in the manner already described in connection with retorts 12 13 14, and, finally, the uppermost retort 18 communicates at one end with the vertical pipe 19. By reason of this construction the gas 10 entering the retorts passes in alternately opposite directions downwardly through the first bank of retorts 12 13 14 and then in like manner upwardly through the second bank of retorts 16 17 18 to pipe 19 and thence 15 to the seal-pot 20, and so to outlet-pipe 21, shown broken off in Fig. 2. The two banks of retorts are respectively contained in chambers 23 24, located in the fire-brick casing 25 and separated by a partition 26. 20 In the bottom of said chambers and below the retorts 14 16 are horizontal partitions 27 28, having vertical channels extending through them. Similar partitions are disposed in said chambers between the retorts 25 and also above the upper retorts 12 and 18. The partition 26 extends down and across the outlet-flue 29, with which flue the vertical pipes 5 and 8 communicate. It will be obvious, therefore, that there is a free channel 30 from the pipes 5 and 8 to the flue 29, thence upward in the chamber 23 through the channels in partitions 27 and the spaces surrounding the retorts 12 13 14, thence through the opening 30 in partition 26 to chamber 24, 35 and so downwardly through the channels in partitions 28 and spaces surrounding retorts 18, 17, and 16, and then to the outlet of flue 29 on the other side of partition 26.

It will be obvious that from the outlet of 40 each generator two gas-passages lead, respectively, to the retorts and to the casing-chambers 23 and 24 inclosing said retorts. In order to divert the producer-gas from the generator into the passage leading to chambers 23 24 and the water-gas into the passage leading to the retorts as these gases are 45 successively produced, I provide in each of the valve-chambers 4 and 7 a double controlling-valve 31 32. The two valves 31 32 are alike and arranged in the same way, so 50 that a description of one will apply to both. Referring to Fig. 4, it will be seen that the valve 31 has an upper convexity 33 and a lower convexity 34, separated by a V-shaped groove. By means of a lug on its upper side 55 it is pivoted to the end of a rod 35. Said rod, as shown in Figs. 5 and 6, extends upwardly through a standard 36 and at its upper portion has a rack-bar 37, the teeth of 60 which engage with a pinion 38, journaled in said standard. The valve 31 by its own gravity normally seats its lower convexity in the bottom of its chamber, and thus closes the 65 passage leading to the casing-chambers 23 24. It may be raised or gradually lowered

when desired by rotating said pinion 38 by means of the hand-wheel 39, and it may be held or clamped in either raised or lowered position by means of the clamping-cam 70, pivoted on standard 36, which cam by lever 71 may be jammed against the rack-bar 37. When the valve is in its uppermost position, its upper convexity 33, as shown in Fig. 4, is seated in the upper part of the valve-chamber, and thus closes the passage leading from 75 the generator to the retorts. When it is in its lowermost position, the passage to the casing-chambers 23 24 is, as stated, closed. Therefore by this single device I am enabled to divert the water-gas coming from the generator to the retorts and the producer-gas coming from the generator to the said inclosing chambers and to close the passage leading to the retorts at the same time as the passage leading to the inclosing chambers is 80 opened, and vice versa. In this way I obviate all danger of admitting producer-gas, which is usually a flame, into the retorts or permitting water-gas to flow into the highly-heated casing-chambers. This danger 85 results in disastrous explosions. It is always present when two separate valves are employed, one controlling the passage to the retorts and the other to the casing-chambers. It may be caused by carelessness on the part 90 of the attendant in not properly operating the valves or the accidental sticking or failure to work of one valve or the other.

Especial attention is called to the fact that the valve is not in frictional contact with 100 anything during its travel from seat to seat, but is widely separated from the adjacent walls, and this is also true of its rod which passes upward through the large passage leading to the retorts. Of course said rod 105 may go through any suitable stuffing-box 72 in passing through the upper wall of the passage; but this box is so far distant from the generator and valve-chamber that there is no danger of any overheating and binding 110 of the rod from this cause. Furthermore, said passage is traversed only by water-gas, which, as is well known, is of much lower temperature than producer-gas. Inasmuch as there is a like valve provided for each generator 115 1 and 2, it is possible to adjust one valve in one position and the other in the other position, as shown in Fig. 3, so that while the producer-gas from one generator is passing around the retorts to heat them 120 the water-gas from the other generator is passing through said retorts; but it is particularly to be noticed that each generator has connection with both retorts and retort-casing, so that in case one generator should 125 become injured or for any cause be thrown out of operation it is possible to continue gas-making with the other generator. In such case the valve of that generator would first be adjusted to divert producer-gas into 130

the casing-chambers to heat them and then shifted to divert water-gas into the retorts until the chambers again require heating, these operations continuing alternately.

5 While producer-gas is being made nitrogen and other impure gases are also generated, which should not be allowed to mingle with the water-gas. In order to get rid of such impure gas, I provide the following construction: On top of each generator and above the main gas-escape outlet is a dome or gas-collecting chamber 40 41. Said domes are provided with detachable covers 42 43 with clamping-bars 44. The two domes are connected by a pipe 45, which at its middle portion communicates with a vertical pipe 46, Fig. 2, which is turned to extend through the wall of and enter the flue 29. On each side of the pipe 46 are valves 47 48. By suitably manipulating the valves 47 48 the nitrogen or other impure gas which rises into and becomes trapped in said domes 40 41, or either of them, may be led through the pipe 46 directly into the flue 29, said pipe 46 thus forming a by-pass around the main gas-escape outlet. At the bottom of each generator are pipes 49 50, which communicate with a source of air-blast (not here shown) and serve to introduce said blast into said generators, as usual, below the grates. Said blast apparatus may also communicate with a pipe 51, which extends into the chamber 23, surrounding the first bank of retorts. In the upper part of the pipe 11 is a rose-nozzle 52, which communicates with a pipe 53, leading from any suitable source of oil-supply. A valve 54 is arranged in pipe 53 for regulating the flow of said oil to said nozzle and is itself controlled by the hand-wheel 55. 35 This oil-flow is preferably kept up continuously during the operation of the apparatus. Oil is also introduced intermittently into the generators by pipe 58, which leads it through an annular chamber 56, surrounding the 40 valve-chamber, and thence by pipe 59 to a branch pipe connecting with nozzles 60, which communicate with the generator at the upper part thereof. The nozzles 60 are provided with regulating-valves 61, and a 45 control-valve 62 is arranged in pipe 59 and operated by hand-wheel 63. By this construction I divide the oil used for carbureting the water-gas between the generator and the retort and am enabled to control accurately the relative proportions of said oil delivered to each. Where all the oil is delivered to the generator, a portion is apt to become carbonized and not vaporized. Where all is delivered to the retorts, a portion is apt 55 to be carried over in liquid state by the gas-current to the condenser, scrubber, or hydraulic main. Where the oil is delivered by numerous pipes into each of the retorts, it is apt not to become completely decomposed. 60 This complete decomposition is secured

when the oil is led into the first retort of a series of retorts and is thus caused to pass successively through all of them.

Steam is delivered into the bottom of the generator for the production of water-gas. 70 The annular chamber 57, surrounding the main controlling valve-chamber, communicates by pipe 64 with any suitable source of steam-supply and by pipe 65 with the ash-pit of the generator. In pipe 64 is a regulating-valve 66, operated by the hand-wheel 67. A manhole provided with cover 68 is arranged in seal-pot 20 to allow access to the interior.

The operation of the apparatus is as follows: Fires are started on the grates of both generators. The covers of the domes being removed, coal, coke, or combustible matter is charged in proper quantity into said generators and the covers replaced and clamped 80 down. The air-blast through pipes 49 and 50 is started. Both controlling-valves are raised to their upper seats. The producer-gas from both generators then passes to pipes 5 and 8 and through the chambers 23 and 24 85 around the retorts. Supplementary blast is also admitted to their chambers through pipe 51. The fuel in the generators is thus raised to proper temperature and the retorts are heated. Oil-valve 54 being opened, a 90 part of the oil for carbonization is admitted to the retorts in the form of fine spray through nozzle 52. Blast is now cut off from one of the generators, as generator 1, Fig. 2. The nitrogen and impure gases which have risen 95 above the main outlet are now trapped in the gas-collecting dome. The controlling-valve 31 is still raised to shut off the passage to the retorts. Valve 65 in steam-pipe 64 is opened by hand-wheel 67, and steam superheated by 100 passage through the annular chamber 57 then passes by pipe 65 to the lower part of the generator. At the same time valve 48 in pipe 45, leading from the dome of generator 1, is 105 opened. The steam rising through the fuel 110 forces the nitrogen and impure gas trapped in the dome out through the pipe 46, and so to outlet-flue 29. As the cubic contents of the space in the dome and generator above the main escape-outlet in which the impure gases 115 are trapped is small, this expulsion of the gases takes place very quickly, so that the controlling-valve 31 may be almost immediately shifted to its lowermost position to 120 cut off the passage leading to the casing-chambers and open the passage leading to the retorts, into which the water-gas now being generated flows. Valve 48 is now closed and the generator is ready to receive its proportion of the carbureting-oil. Valve 62 being opened, 125 oil enters the generator by pipe 59 and injector 61 above the fuel. The carbureted water-gas then mixes with and is enriched by the oil-gas made in the retorts, and from the retorts fixed carbureted water-gas then 130

goes to the holder or any desired intermediate apparatus. In the meantime the producer-gas from generator 2 is passing around the retorts. When generator 1 becomes too cold to make good gas—that is, to properly decompose the steam and vaporize the oil—its oil-supply is shut off; but the inlet of steam is continued for about three-quarters of a minute, so as to drive out all of the good gas, which would be wasted if the oil and steam were shut off simultaneously. Lastly, the steam-supply is shut off, the valve 31 brought back to its uppermost position, as in Fig. 2, the air-blast is turned on, and producer-gas made and used to heat the retorts until all the fuel is consumed. While this is going on the second generator is set in operation to produce water-gas in the manner already described. The two generators are thus used alternately.

I claim—

1. In combination with a generator for making water-gas and producer-gas, a retort and a casing having a chamber containing said retort, passages connecting said generator with said chamber and said retort and a device operating by a single movement to divert the producer-gas from said generator to the passage leading to said casing-chamber or the water-gas from said generator to the passage leading to said retort.

2. In combination with a generator for making water-gas and producer-gas, a retort, and a casing having a chamber containing said retort, passages respectively connecting said generator with said chamber and said retort, and a valve operating by a single movement to open one passage and close the other.

3. In combination with a generator for making water-gas and producer-gas, a retort, and a casing having a chamber containing said retort, a valve-chamber communicating with the gas-outlet of said generator, passages respectively connecting said valve-chamber with said casing-chamber and said retort and a valve movable in said valve-chamber and operating by a single movement to open one passage and close the other.

4. In combination with a generator for making water-gas and producer-gas, a retort and a casing having a chamber containing said retort, a valve-chamber communicating with the gas-outlet of said generator, passages respectively connecting said valve-chamber with said retort and said casing-chamber, valve-seats in said valve-chamber at the entrance of said passages and a movable valve in said chamber constructed to enter either seat.

5. In combination with a generator for making water-gas and producer-gas, a retort and a casing having a chamber containing said retort, a valve-chamber communicating with the gas-outlet of said generator, passages respectively connecting said valve-

chamber with said retort and said casing-chamber, valve-seats at opposite sides of said valve-chamber at the entrance of said passages and a movable valve in said valve-chamber constructed to enter either seat.

6. In combination with a generator for making water-gas and producer-gas, a retort and a casing having a chamber containing said retort, a valve-chamber communicating with the gas-outlet of said generator, passages respectively connecting said valve-chamber with said retort and said casing-chamber, valve-seats in the upper and lower walls of said chamber at the entrance of said passages and a valve in said chamber vertically movable to enter either seat.

7. In combination with a generator for making water-gas and producer-gas, a retort and a casing having a chamber containing said retort, passages respectively connecting said generator with said chamber and said retort, a movable valve having opposite convex faces and correspondingly-formed seats for said valve at the entrance of said passages.

8. In combination with a gas-generator for making water-gas and producer-gas, a retort and a casing having a chamber containing said retort, and passages respectively connecting said generator to said retort and said casing, a movable gravitating valve constructed normally to open one passage and close the other.

9. In combination with a gas-generator for making water-gas and producer-gas, a retort and a casing having a chamber containing said retort, and passages respectively connecting said generator to said retort and said casing, a movable gravitating valve constructed normally to close the passage leading to said casing-chamber.

10. In combination with a gas-generator for making water-gas and producer-gas, a retort and a casing having a chamber containing said retort, and passages respectively connecting said generator to said retort and said casing, a movable valve operating by a single movement to close one passage and open the other and means for mechanically holding said valve in either position.

11. In combination with a gas-generator for making water-gas and producer-gas, a retort and a casing having a chamber containing said retort, and passages respectively connecting said generator to said retort and said casing, a valve movable by gravity to close one passage and open the other and means for raising said valve.

12. In combination with a gas-generator for making water-gas and producer-gas, a retort and a casing having a chamber containing said retort, and passages respectively connecting said generator to said retort and said casing, a valve movable by gravity to close one passage and open the other, means

for raising said valve to close the aforesaid opened passage and means for holding said valve in raised position.

13. In combination with a gas-generator, a retort, a heating-chamber for said retort, means for conducting water-gas and producer-gas from said generator respectively to said retort and heating-chamber, means for admitting a steam-jet below the fuel-space in said generator and means, independent of said means for conducting water and producer gas and communicating with the generator above said fuel-space, for conducting nitrogen or other impure gas expelled by said steam-jet from said generator to said heating-chamber.

14. A gas-generator for making water-gas and producer-gas having a charging-opening and a single escape-opening for both water-gas and producer-gas, a duct communicating with said escape-opening, a valve in said duct disposed in proximity to said escape-opening, a conduit independent of said charging-opening communicating with said generator above said escape-opening and means for opening and closing said conduit.

15. A gas-generator for making water-gas and producer-gas, having a single escape-outlet for both water-gas and producer-gas, a controlling-valve therefor, a dome disposed above said generator and having a fuel-charging opening, a conduit independent of said charging-opening leading from said dome and means for opening and closing said conduit.

16. The combination of a generator for making water-gas and producer-gas, having

a charging-opening in its upper wall, a single escape-outlet for both water-gas and producer-gas in its side wall and a valve controlling said gas-outlet, a conduit communicating with said generator below said charging-opening and above said gas-escape outlet and means for opening and closing said conduit.

17. The combination of (1) a gas-generator, for making water-gas and producer-gas, having a charging opening in its upper portion, a single escape-outlet for both water-gas and producer-gas and a controlling-valve therefor; (2) a heating-chamber receiving producer-gas from said generator; (3) a conduit connecting said generator above said outlet and below said charging-opening with said heating-chamber and means for opening and closing said conduit.

18. In combination with a generator for making water-gas and producer-gas, having a main escape-outlet and a chamber above said outlet, a retort and a casing having a chamber containing said retort, passages leading from said generator respectively to said retort and said chamber-casing and a valve constructed to control said passages, a separate conduit connecting said generator-chamber with said casing-chamber, and means for opening and closing said conduit.

In testimony whereof I have signed my name to this specification in the presence of two subscribing witnesses.

WALTER A. FOURNESS.
